UNITED STATES PATENT OFFICE.

GEORGE T. JOHNSON, OF MELROSE, MASSACHUSETTS.

TOILET-PAPER CABINET OR FIXTURE.

No. 921,843.

Specification of Letters Patent.

Patented May 18, 1909.

Application filed January 9, 1909. Serial No. 471,505.

To all whom it may concern:

Be it known that I, GEORGE T. JOHNSON, a citizen of the United States, residing at Melrose, in the county of Middlesex, State of Massachusetts, have invented a certain new and useful Improvement in Toilet-Paper Cabinets or Fixtures, of which the following is a specification, reference being had therein to the accompanying drawings.

10 The invention finds embodiment in a cabinet or fixture constructed to receive a package of toilet-paper composed of a number of oblong sheets assembled together and bent or folded on a transverse line so that the opposite end-portions are close together, the said cabinet or fixture having a delivery-slit adjacent the position of the leading edge of the package, and also being provided with manually-operated means for feeding the sheets 15 singly edgewise in a correspondingly doubled state into the said slit and far enough through the same to enable the outwardly-projecting portion of a sheet to be grasped by hand and the sheet pulled out.

20 The invention comprises a manually-operated feeder which works within the bend of the package and engages with the inner surface of the innermost sheet, at the bend. Also, inclined guide-walls located at opposite 25 sides of the delivery-slit and converging toward the latter, to guide the respective side-portions of the advancing sheet toward the slit, bring them close together, and facilitate the entrance of the doubled sheet into the 30 slit. Also, a former-block arranged to engage with the rear edge of the package at the bend and press the leading portions of the sheets, at the bend, forward into the space between the converging guide-walls. Also, 35 provisions for causing an edgewise displacement of the side-portions of the package relative to each other so that the marginal portions of a delivered sheet shall lap past each other, at front and rear respectively, thereby 40 increasing materially the width of the folded sheet as delivered. Also, other features to 45 which reference will be made in the course of the description.

A cabinet or fixture embodying the various 50 features which are comprised in the invention is shown in the drawings, in which,—

Figure 1 is a view of the said cabinet or fixture, and a package of paper therein, in vertical section in the plane indicated by the 55 dotted line 1, 1, of Fig. 2. Fig. 2 is a view of the said cabinet or fixture in elevation, look-

ing from the right in Fig. 1. Fig. 3 is a view in section in the same plane as Fig. 1, but with the cabinet or fixture opened by swinging back the movable end-piece and the 60 parts in connection therewith, the package of paper being shown in elevation instead of in section as in Fig. 3. Figs. 4 and 5 are views in horizontal section in the planes indicated by the dotted lines 4, 4, in Fig. 1, and 65 5, 5, in Figs. 1 and 3. Fig. 6 shows a sheet of paper in the shape in which it is delivered from the cabinet or fixture.

Having reference to the drawings,—The opposite side-pieces of the body of the cabinet or fixture are shown at 1, 1, and 2 is the end-piece at the delivery-end, 3 the top of the said body, and 4 the bottom thereof. A movable end-piece is shown at 5, and at 6 is a hinge connecting the said end-piece 70 with the bottom 4. Fig. 1 shows the said movable end-piece in closed position, and in Fig. 3 it is shown swung back to open up the cabinet or fixture.

A package of paper formed of sheets laid 80 together and bent transversely upon itself as already described herein is shown at 7. A securing wire 8 is passed through the end of one side-portion of the package, near the corner thereof, and a similar wire, 8^a, is 85 passed through the end of the other side-portion. After insertion of the package into the cabinet or fixture, the projecting portions of the wires 8, 8^a, are engaged with hooks 9, 9^a, which are provided upon the 90 sides 1, 1, of the cabinet or fixture. By means of such wires, and in consequence of the engagement of the same with the hooks 9, 9^a, the ends of each sheet are detained 95 until the sheet is forcibly pulled forward by hand and thereby torn loose from the wires. Also, when the number of sheets remaining in the cabinet has become small, the opposite side-portions of the said sheets are held 100 extended and thus prevented from collapsing toward the bend of the package.

The delivery-slit in the end-wall 2 is indicated at 10. Its length from one end to the other thereof exceeds that from the bend of the package to the ends of the side-portions 105 of the latter, so that a doubled sheet may pass out through the slit in a flat state extended at full length. The converging walls at the opposite sides of the said slit are shown at 11, 11. The extent of the spread or divergence of the innermost portions of these walls is sufficient to admit the bent 110

portion of a sheet readily between them, even when the side-portions of the sheet are expanded somewhat widely apart. A former-block is shown at 12, mounted upon 5 the hinged end-piece 5 of the cabinet. When such end-piece is swung away from the body of the cabinet, so as to expose the interior of the latter, a package of paper may readily be inserted with the said body. 10 After the package has been inserted, and its wires have been engaged with the hooks 9, 9^a, the closing movement of the end-piece 5 carries the shaped portion of the former-block against the rear edges of the sheets of 15 the package, forcing the said sheets forward and causing their leading edges to enter the V-shaped space between the converging walls 11, 11, and partly fill such space. The acting end of the former-block is rounded 20 transversely and so shaped that the bends of the innermost sheets of the package will be pressed forward farthest into the said space.

One form of manually-operated feeder is 25 shown, and as shown herein embodies certain features of my invention, but I do not limit myself in all cases to the employment of this particular form. Thus, at 13 is a block furnished with a frictional acting portion 14 for engagement with a sheet of paper, so that when the feeder is moved forward the said acting portion shall engage with the sheet and advance the latter. I prefer to employ a covering or pad of india-rubber, but other means of engagement with the sheet may be utilized. Various sheet-feeding devices suitable for use in the present connection are known in the arts, and in some cases may be employed without 30 involving a departure from the general principles of the present invention. The drawings show the frictional portion 14 as a covering in the form of a continuous corrugated band or ring of rubber which may be shifted 35 around from time to time to bring fresh portions of its surface into position for action. For the purpose of actuating the feeder, an arm or extension 15 projecting from the block 13 is pivotally engaged with one arm of 40 a lever 16, which latter is mounted pivotally at 17 in connection with a support 18 constituted by two parallel plates carried by the hinged end-piece 5. The lever 16 is located between such plates, and is covered 45 and shielded thereby. In closing the end-piece 5 against the body of the cabinet after a package has been placed within the latter, the lever-support 18 and lever pass into the narrow space between the two side-portions 50 of the package. Being inclosed between the two plates constituting the lever-support, the lever is protected from contact with the sheets of the package in its movements. The lever-support and casing 55 constitute a separator for the two side-portions

of the package, which prevents such side-portions from crowding in against the feeder so as to interfere with the working thereof, and thereby also protects the sheets from being torn or accidentally displaced by the 70 movements of the feeder. Also, being in line with the delivery-slit 10 it prevents displacement of the package laterally. The side-portions of the innermost sheet rest against the smooth surfaces of the said lever-support and casing, which facilitates their movement in being advanced and withdrawn. 75

For convenience in operating the feeder, a projection or handle 19 is provided in connection with the lever 16. This projection or handle extends laterally out through a curved slot 20 in one of the plates of the lever-support, and also through a notch shown at 20^a, Fig. 5, in the adjacent side-wall of the body of the cabinet. The said slot and notch permit play of the projection or handle in the operation of the lever. A spring 21, which has an end thereof engaged with the forwardly-projecting flange 22 of 90 the end-piece 5, and its other end engaged with projection or handle 19, holds the lever and feeder normally in retracted positions, and acts to retract them after they have been operated to feed a sheet. The pivotal connection of the feeder with its operating lever 16 permits the acting portion of the feeder to press with uniform force, under the influence of gravity or a spring, against the 95 surface of the innermost sheet of the package, 100 within the bend of the latter, and enables the said feeder to conform to the thickness of the assemblage of sheets so that the device acts as efficiently at one time as at another, whether a full package be contained in the 105 cabinet or a more or less completely exhausted one.

To prevent play of the feeder sidewise with relation to the lever 16, the arm 15 is made double, or in two parallel members, 110 the latter receiving between them the block 13 and being fastened thereto, and the free extremities of said members receiving between them an extremity of the lever 16 so as to clasp the latter extremity at opposite 115 sides. The feeder is connected with the operating lever 16 by means of a hinge-connection so contrived as to prevent accidental disconnection of the feeder from the lever, and yet permit the lever to be intentionally 120 disconnected and removed, and again applied and connected, freely and readily, whenever desired, as, for instance, for the purpose of replacing the frictional covering 125 14. To this end the extremities of the members of arm 15 are radially slotted at 23 to receive portions of a pin 24 which project at opposite sides of the said lever. The outer edge of the said extremities also are made concentric with a center adjacent the 130

inner ends of the said slots. A pin 25 projects at opposite sides from the lever 16 close to the said outer edges. The positions of the slots in the said members, and of pin 25 upon the lever, are such that in the working positions of the feeder the pin 25 prevents disconnection of arm 15 from pin 24 of the lever. When, however, the end-piece 5 is turned down into the position occupied by it in Fig. 3, and lever 16 is moved so as to swing its end carrying the pin 24 upward in the said figure, the feeder and arm 15 may be turned around pin 24 until slots 23 are so disposed as to permit arm 15 to be lifted off pin 24 without interference on the part of pin 25. With the lever in the same or a similar position the feeder may be conveniently and readily applied to the lever.

At 26, 26, are side-pressers, located at opposite sides of the chamber or cavity of the cabinet, and arranged to exert inwardly-directed pressure upon the exterior surfaces of the side-portions of the package adjacent the mouth of the V-shaped space between the converging walls 11, 11. In this instance, the said side-pressers are constituted by springs which are secured to the side-pieces near the rear end of the cabinet and extend forward toward the end-wall 2, the forward ends of the said springs being free to move inward and outward transversely within the said chamber or cavity. The pressure of the side-pressers is applied to those portions of the package which are nearest the mouth of the V-shaped space between the converging walls 11, 11. As a package of paper is inserted into the cabinet it passes in between the said side-pressers. As the number of sheets left in the package diminishes in consequence of the delivery of sheets from the interior of the package, the side-pressers act to press the side-portions of the outer sheets inwardly toward the middle, so as to place them in the best position for entering between the converging walls 11, 11, and passing into the slit 10.

In operation, when the feeder is caused to advance from its normal retracted position shown in Fig. 1, it pushes the bend of the innermost sheet forward so that the leading edge of each sheet at and adjacent the bend is caused to pass through the delivery-slit and protrude far enough to be grasped by hand. The wires 8 and 8^a which are engaged with the ends of the side-portions of the package, and also with the hooks 9, 9^a, or other retaining devices, hold back the ends of the sheet while the bend is being advanced, the result being that the bend alone, being free to advance, is thrust forward as described. In being fed, the sheet swings more or less about the points of connection with the wires. In order that this may not result in a crumpling of the rear portion of the sheet at the bend, I preferably apply

the wires to the package at or near the rear corners of the side-portions, as shown, so that when the inner sheet is fed by the action of the feeder in the manner described the bend of the sheet swings upward clear 70 and free from the bends of the next succeeding sheets, entirely across the width of the package.

In order to cause an edgewise displacement of the side-portions of the package 75 with respect to each other, so that, the edge-portions of a sheet shall lap past each other, at front and rear respectively, substantially as in the case of the sheet *a*, Fig. 6, thereby increasing materially the width of the folded 80 sheet as delivered, the hooks 9, 9^a, or other retaining devices employed, are offset with relation to each other; that is to say, one thereof is located farther rearward than the other. This produces a kind of twist of the 85 package when the wires 8, 8^a, are applied to the retaining devices, the twist and displacement being represented in Fig. 3. In order to increase the extent of this relative displacement without it being necessary to set 90 the hook 9^a a considerable extent rearward of the hook 9, which would necessitate making the cabinet larger in the direction from front to rear, the wire 8^a is engaged with the corresponding end of the package of paper 95 at a greater distance from the rear corner of such end than the distance from the point at which the wire 8 is engaged with the other end of the package to the corresponding corner of the latter.

An advantage of the herein-described cabinet or fixture is the fact that the feeder will push forward only the sheet with which it immediately makes contact. Delivery of two sheets at a time will not occur. Another 100 advantage is that the corner-portion of such sheet which has been caused to protrude through the delivery-slit must be grasped by hand before the feeder is allowed to return; otherwise, the feeder will take back the sheet 105 with it, drawing such corner-portion into the cabinet or fixture again. The former-block serves to prevent rearward displacement of the top sheet by the movement of the feeder in returning. When the movable end-piece 110 5 is swung open into the position occupied by it in Fig. 3, the feeder rests upon the up-turned end of the former-block, which presents it in proper position for entering the opening or space between the side-portions 115 of the package when the end-piece is closed 120 into place against the body of the cabinet or fixture.

I claim as my invention:—

1. In a toilet-paper cabinet or fixture, in 125 combination, a holder adapted to contain a folded package of paper having both side-portions extended in one direction, and provided with a delivery slit at one edge of such package, and a feeder which works between 130

the said side-portions and by engagement with the inner surface of the inner sheet within the bend thereof advances the leading edge of such sheet partly through the said 5 delivery-slit.

2. In a toilet-paper cabinet or fixture, in combination, a holder adapted to contain a folded package of paper having both side-portions extended in one direction, and provided with a delivery-slit at one edge of such 10 package, means to detain the end-portions of the sheets, and a feeder which works between the side-portions of the package and by engagement with the inner surface of the 15 inner sheet within the bend thereof advances the leading edge of such sheet at the bend partly through the said delivery-slit.

3. In a toilet-paper cabinet or fixture, in combination, a holder adapted to contain a folded package of paper having both side-portions extended in one direction, and provided with a delivery-slit at one edge of such package, engaging devices offset with respect to each other to displace the side-portions 20 of the package edgewise relative to each other, and a feeder which advances a sheet edgewise from said package through the delivery-slit.

4. In a toilet-paper cabinet or fixture, in combination, a holder adapted to contain a folded package of paper having both side-portions extended in one direction, and provided with a delivery-slit at one edge of such package, engaging devices offset with respect to each other to displace the side-portions 25 of the package edgewise relative to each other, and a feeder which works between the side-portions of the package and by engagement with the inner surface of the inner sheet within the bend thereof advances the leading edge of such sheet at the bend partly 30 through the said delivery-slit.

5. In a cabinet or fixture for toilet-paper, in combination, a holder adapted to contain a folded package of paper with side-portions 35 extending in one direction, and constructed with a delivery-slit at one edge of the folded package, engaging means for fastenings or wires in connection with the rear corners of the package, and a feeder working between the said side-portions and engaging with the inner surface 40 of the inner sheet at the bend to advance the leading edge of such sheet at the bend partly 45 through the delivery-slit.

6. In a cabinet or fixture for toilet-paper, in combination, a holder adapted to contain a folded package with the side-portions of the latter extending in one direction, and constructed with a delivery-slit at one edge of the folded package and with guides converging 50 to the said delivery-slit, and a feeder working between the side-portions of the package and engaging with the inner surface 55 of the inner sheet at the bend to advance the face of the inner sheet at the bend to advance

the leading edge of such sheet at the bend through the delivery-slit.

7. In a toilet-paper cabinet or fixture, in combination, a holder adapted to contain a folded package of paper having both side-portions thereof extended in one direction, and constructed with a delivery-slit at one edge of the folded package and with guides converging to the said delivery-slit, means to press the package edgewise between the 75 said guides, and a feeder acting upon the bend of the inner sheet to advance the latter partly through the delivery-slit.

8. In a toilet-paper cabinet or fixture, in combination, a holder adapted to contain a folded package of paper having both side-portions thereof extended in one direction, and constructed with a delivery-slit at one edge of the folded package and with guides converging to the said delivery-slit, means to detain the ends of the side-portions of the package, means to press the bend of the package edgewise between the said guides, and a feeder acting upon the bend of the inner sheet to advance the latter partly 85 through the delivery-slit.

9. In a toilet-paper cabinet or fixture, in combination, a holder adapted to contain a folded package of paper having both side-portions thereof extending in one direction, 95 and constructed with a delivery-slit in line with the middle of the thickness of the folded package, and with guides converging to the said delivery-slit, means for advancing the bend of the package between such guides, 100 means for detaining the ends of the side-portions of the package, and a feeder engaging with the inner sheet at the bend thereof to advance the latter through the delivery-slit.

10. In a toilet-paper cabinet or fixture, in combination, a holder adapted to contain a folded package of paper having both side-portions thereof extending in one direction, and constructed with a delivery-slit in line 110 with the middle of the thickness of the folded package, a separator between the side-portions of the folded package, and a feeder working within the bend of the package and engaging the inner surface of the inner sheet 115 to advance the latter through the delivery-slit.

11. In a toilet-paper cabinet or fixture, in combination, a holder adapted to contain a folded package of paper having the side-portions thereof extending in one direction, and constructed with a delivery-slit at one edge of the package, a separator entering between the said side-portions, and a feeder supported by the said separator within the bend of the package and acting upon the inner sheet 125 to advance such sheet through the delivery-slit.

12. In a toilet-paper cabinet or fixture, in combination, a holder adapted to contain a 130

folded package of paper having the side-portions thereof extending in one direction, and constructed with a delivery-slit at one edge of the package, a separator entering between 5 the said side-portions, a feeder working within the bend of the package and acting upon the inner sheet to advance the latter through the delivery-slit, and an actuating-lever for such feeder supported by the said separator.

10 13. In combination, the operating lever, a pivotal-pin carried thereby, a feeder having an arm with radial slot in its end and the extension of such end circularly curved, and the locking-pin on said lever engaging with 15 said curved exterior to keep the feeder-arm locked in pivotal connection with the operating lever when in normal working position but permitting the arm to be released for disconnection by the turning of the parts into 20 an abnormal relative position.

14. In a toilet-paper cabinet or fixture, in combination, a holder adapted to contain a folded package of paper with both side-portions thereof extending in one direction, and 25 constructed with a delivery-slit at one edge

of the folded package and with the end-wall opposite said slit movable, and a separator and a feeder which are carried by the said movable end-wall and are caused by the movement of the latter into place to enter 30 between the side-portions of the package.

15. In a toilet-paper cabinet or fixture, in combination, a holder adapted to contain a folded package of paper having both side-portions extended in one direction, and provided with a delivery-opening at one edge of such package, a feeder-arm working in the space between such side-portions and having a frictional surface to engage with the inner surface of the inner sheet at the bend, and 35 an operating lever with which said feeder is connected pivotally so that it may press against the said surface. 40

In testimony whereof I affix my signature in presence of two witnesses.

GEORGE T. JOHNSON.
